Primary Examiner — Mehri F Bajoul(57) **CLAIM**

The ornamental design for a game pad, as shown and described.

DESCRIPTION

FIG. 1 is a front and top perspective view of a game pad, showing, my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of a portion labeled, ‘FIG. 9’ in FIG. 1.

The even dash-dash broken lines in the figures illustrate portions of the game pad that form no part of the claimed design. The long-short dash broken lines in FIGS. 1 and 9 are for the purpose of depicting the bounds of the enlarged portion and form no part of the claim.
